WEFT THREADS CARRYING DEVICE FOR CIRCULAR WEAVING LOOMS

Giusto Casati, Barzano, and Carlo Cazzaniga, Monticello, Italy

Application July 3, 1951, Serial No. 234,992

Claims priority, application Italy January 3, 1951

7 Claims. (Cl. 139—13)

It is an object of the present invention to provide a weft threads carrying device for circular weaving looms, which among other features is characterized in that the weft carrying spool is carried by a carriage which is attracted by an electromagnetic roller. The device according to the invention is illustrated by way of example in the accompanying drawing, in which:

Fig. 1 shows the device, in a complete side view,

Fig. 2 shows diagrammatically, the detail of the rollers, and the direction of their rotation in respect to the warp threads;

Fig. 3 is a perspective view of the electromagnetic roller and its respective connection means to the weaving loom;

Fig. 4 is a front view of the weft spool carrying carriage;

Fig. 5 is a front view of the position taken by the bobbin when it is placed on the carriage and illustrates the angle which is formed by the spool axis with the warp threads;

Fig. 6 is a left hand view in respect to Fig. 4, of the carriage.

Fig. 7 is a view similar to Fig. 5 but showing a side view of the spool during the lift of the warp threads

Figs. 8, 9 are respectively a larger scale front view, and top view showing the detail of the assembling on the carriage of the loom stopping operation devices in the case when the weft thread is broken, in normal working position.

Figs. 10 and 11 show on a larger scale the position taken by the loom stopping devices after the weft thread is broken;

Fig. 10a is a sectional view on an enlarged scale taken along line 10a—10a of Fig. 10;

Figs. 12 and 13 are a larger scale side view and top view respectively, of the detail of the loom stopping device in the case of a weft thread breaking or abnormal running;

Figs. 14 and 15 are a larger scale side view and top view respectively, of the automatic loom stopping operation device, in the case when the carriage is displaced in respect to the electromagnetic roller.

Referring now to the drawings, the weft carrying device according to the invention is formed by an electromagnetic roller 1 (Fig. 1), which is pivoted on its spindle 2 and supported by the arms 3, 4; the latter are in turn secured to a sleeve M rotating on the central weaving loom shaft d (Fig. 3), the electric current being brought to the roller by means of the brush 5 and the collector 6; an auxiliary roller 7 supported by and rotating on screws 8, 9 is located beside the first roller 1, and said screws 8, 9 are in turn fixedly secured to the arms 10 and 11 respectively, which are branched out from arms 3, 4 joined together by the rod 12. In order to effect the rotation of roller 1 around its spindle 2, when it is displaced around the weaving loom, there is provided on the end of the spindle 2 a bevel gear 13 which engages with a toothed rim b of a plate, which is secured

2

in a manner not shown to the headpiece of the guide tube c which encircles the main shaft d of the weaving loom. The roller 1 rotates in the inner part of the warp threads fo; the carriage A which includes rollers 14, 15 adheres to said roller 1 on account of its electromagnetic attraction since the two rollers 14, 15 are formed of magnetic material (Figs. 1 and 4), both being pivoted on their spindles, which are centered on the bars 16, 17 of nonmagnetic material and said bars being joined together by the rod 18 of magnetic material having also field intensifying purposes. Thus the carriage A includes elements 14—18, among other elements indicated below. Both rollers 14, 15 having a length equal to that of roller 1, are joined together by rubber belts 19, 20 for joined rotation; said belts while slightly projecting from the profile of the rollers, hinder the direct contact of rollers 14 and 15 with the electromagnetic roller 1, whereby the warp threads are obliged to pass between said magnet roller and the rubber belts 19, 20. The roller 14 is provided with headpieces 14' and 14'' having a slightly greater diameter than the remainder of roller 14 and a toothed periphery and which are able to adjust the carriage position with respect to roller 1; the purpose of the teeth is to prevent, during the carriage rotation, the warp threads fo from suddenly jumping since they can insert themselves between the teeth interstices and thus maintain their perpendicularity. The carriage A is further provided with a funnel member 21 secured to the rod 18 and in which—on account of equal conical shape of the weft threads carrying spool—the latter can be housed with its cone-shaped part. Funnel 21 is provided on its front with a longitudinal slot 22 to facilitate the insertion of the weft threads unwinding from spool 23; said thread leaving the funnel is guided between two metallic discs 24, which are secured below the funnel 21, so as to adjust the tension of the thread before passing in the thread guide 25 (Figs. 4, 5) the thread guide being pivoted on the bent arm 26 secured to the bar 17. Figs. 5 and 7 respectively show the position taken by the weft thread carrying spool with respect to the warp threads fo, in side view, and between the lifted warp threads respectively. The guide 25 has a V-formed section (Fig. 10a), which is suitably tapered towards its lower part in order to quickly receive the weft thread ft without threading. In the case of a weft thread break, the loom stopping device illustrated in Figs. 8, 9, 10, 11, will act to stop the loom. Said device consists of a lever 27, one end of which is secured to the guide 25, whereas the other is pivoted on the rod 28 sliding in two holes 28' and 28'' in the bars 17 and 16 respectively, the rod 28 being in turn pivoted on two arms 28b secured below the bar 16; the upper end of the rod 28 being suitably shaped, exerts a lever action on part 29 having an end 29' and a projection 29''. Part 29 is set on a pivot 29i on bar 16, and the other end of part 29 is provided with a pin 30, on which the disc 30 having a diameter equal to the toothed portion 14' of the roller 14 of the carriage A is rotatably mounted. Said device 27, 28, 29, 30 which is put in action by the breaking of the weft thread ft, operates the lever system formed by the rotatable disc 32, which is pivoted on a bar 33, passing over arm 10, which slides in a guide 33f provided with a spring 34 weaker than spring 31 and acting on bar 33 to urge the same and disc 32 lightly toward disc 30; said bar is pivoted on the upper end of rod 35 which is in turn pivoted on the rod 36 secured also to the arm 10. An end 35' of rod 35 is bent at a suitable angle and acts like a lever on a rod 37 secured to the support of the mercury bulb 38; pivoted on rod 12. In case of a displacement of carriage A with respect to the electromagnetic roller 1, provision is made of another loom stopping

device comprising a ring 39 located over a second smaller ring 40 provided with cap-screws 41, 42, which are respectively slidingly arranged in slots 3, 3's in the arm 3 and whereby the screw heads bear against the arm; such slots are provided with springs 43, 44. To the head of the screw 42 is secured a bar 45 pivoted on the rod 46, which is jointed in turn to the rod 47, acting as a lever on the support of another mercury bulb 48 pivoted on the rod 12. The above set forth weft carrying device operates as follows: after having put in rotation the sleeve M of the circular weaving loom on which this device is fitted, the rollers 14, 15, as shown diagrammatically in Fig. 2, rotate round the main shaft d of the loom; in the direction of arrow x and then the bevel gear 13, keyed on the pin 2 of the electromagnetic roller 1 (which may, if desired, be substituted by a permanent magnet) and engaging with the toothed rim b rotates also the roller 1, in the direction of arrow y; consequently the rollers 14—15 of the carriage A which are placed outside the warp threads fo are attracted by roller 1 and put in rotation in the direction of arrows z, z'. Thus the auxiliary roller 7 being in contact with roller 14 rotates on its spindle in the direction of the arrow y'; and said roller prevents also the carriage A from sliding on the face of roller 1; in this manner there are provided two rotation directions, which allow the rollers to "roll" on the warp threads fo. The weft thread ft (Figs. 8, 10) which unwinds from the spool 23 housed in the funnel 21, is carried by means of the guide 25 between the warp threads fo and thus performs the weaving of the fabric. The device stopping the loom in case of a break in a weft thread ft operates in the following way: in normal working position, the stretched weft thread ft, coming out from the guide 25, keeps the latter in the inclined position shown in Fig. 8; and the parts 27, 28 take also the position shown in said figure, equilibrating the action of the spring 31, which tries to rotate the shaped part 29 on its spindle 29'; spring 31 being a leaf spring fixed to one side of lever 29 and extending around pivot 29' to urge lever 29 from the position of Fig. 9 to that of Fig. 11. When the breaking of the weft thread ft occurs the guide 25 being freed from the thread stretch, takes the position shown on Fig 10 as the lever 29 turns under the action of the spring 31, whereas the rod 28, which in the normal equilibrium position (Figs. 8, 9) bore just lightly on the projection 29' of part 29, is pushed by the action of the spring 31 towards the side of said projection 29', so as to bear on the end 29' of the part 29; whereby the disc 30 is displaced, passes the plane of warp threads fo (Figs. 10, 11) and pushes against the rotating disc 32, displacing thereby the bar 33 (Fig. 13), which in turn pushes the rod 35 in manner that its end 35', bent at a suitable angle, is displaced in opposite direction, placing again in equilibrium, on the plane, the mercury bulb 38 and thus closing the circuit which determines the loom stopping. As soon as the weft thread is again stretched, the part of the device on the carriage A takes automatically its normal position (Figs. 8, 9), while the remaining part of the operating device is brought in its normal position by the spring 34; it is understood that it is necessary to start again the loom by operating the switch provided for this purpose. In the case when the carriage A is displaced in respect to the electromagnetic roller 1, the other loom stopping device acts as follows: (Fig. 14) the toothed part 14' of the carriage roller 14, projects slightly, in its normal running position on the electromagnetic roller 1, so as to push the ring 39, located thereupon, in the direction towards the loom center, whereby both screws 41, 42 secured to the ring 40 bearing on the ring 39, are displaced in the same direction and thus the lever system 45, 46, 47 brings the mercury bulb 48 in non-equilibrium position, leaving open an electric circuit. As soon as the carriage A is displaced, on account of an

abnormal operation of the latter, in respect to the roller 1, the toothed rim 14' of roller 14 allows the ring 39 to move to the left, as viewed in Fig. 14, on account of the action of the springs 43, 44 on the screws 41, 42 and a very little displacement is enough to restore the mercury bulb equilibrium and thus cause the closing of a circuit which determines the loom stopping.

We claim:

1. A weft thread carrying device for circular weaving looms comprising, a main loom shaft, a magnetic roller, an auxiliary roller adjacent said magnetic roller, a sleeve rotatably mounted on said main shaft, connecting arm means securing said magnetic and auxiliary rollers to said rotatable sleeve, a carriage having two rollers of magnetic material adapted to be located outside the warp threads and almost adherent to said magnetic roller, resilient belts arranged on said two rollers to maintain the latter spaced from said magnetic roller, a funnel adapted to carry a weft thread spool and a V-shaped, bent weft thread guide tapered towards its lower part, an arm whereon said guide is pivoted, and a bar of non-magnetic material to which said arm and funnel are secured and which forms parts of said carriage.

2. A device as claimed in claim 1, wherein said funnel is inclined to said main shaft to support the weft thread spool in an oblique position in respect to the main shaft of the loom.

3. A device as claimed in claim 1, including two automatic loom stopping devices, one of which operates in the case of a weft thread breaking, and the other in the case of the displacement of said carriage in respect to said magnetic roller.

4. A device as claimed in claim 3, wherein the automatic loom stopping operating device for the case of a weft thread breaking comprises a lever means connected to said weft thread guide and controlled by its position, spring means connected to and acting in combination with said lever means, a rotating disc on said lever means maintained in equilibrium by the action of said lever means and said spring means and being grazed by the warp threads having a perpendicular position in respect to it, a second rotating disc adjacent said first disc and located on said connecting arm means, a system formed by bars and by a rod having a bent end to which said second disc is secured, a mercury bulb on said connecting arm means to effect the closure of an electric circuit and thus the loom stopping and this when said equilibrium is destroyed at the moment of the breaking of the weft thread, whereby said first disc is caused to be displaced with respect to the warp threads and exerting a pressure on said second disc, and whereby further said mercury bulb is caused to be brought again in equilibrium.

5. A device as claimed in claim 3, wherein the automatic loom stopping operation device for the case of a displacement of said carriage in respect to said magnetic roller comprises a first ring bearing on said magnetic roller, a second ring located over the first ring, two guide screws secured to said first ring and being able to slide in holes which are provided in said connecting arm means, spring means urging said screws toward said carriage, a lever-and-rod system connected to one of said screws, a mercury bulb connected to and maintained in equilibrium position by said lever-and-rod system, which position is destroyed as soon as one of said carriage forming rollers is displaced in respect to the said electromagnetic roller, whereby the respective electric circuit is closed, thus determining the loom stopping.

6. Weft thread carrying apparatus for circular weaving looms comprising, in combination, a main loom shaft; support means turnably mounted on said main loom shaft for rotation thereabout; a first magnetic roller turnably supported on said support means distant from said main loom shaft for rotation about an axis parallel to the latter; a carriage adapted to be located on the opposite

side of warp threads from said first magnetic roller and including a second magnetic roller parallel to said first roller and located next to the same by magnetic attraction; band means passing about said second roller to prevent the latter from contacting said first roller; and spool carrying means mounted on said carriage for carrying a weft thread spool.

7. Weft thread carrying apparatus for circular weaving looms comprising, in combination, a main loom shaft; support means turnably mounted on said main loom shaft for rotation thereabout; a first magnetic roller turnably supported on said support means distant from said main loom shaft for rotation about an axis parallel to the latter; a carriage adapted to be located on the opposite side of warp threads from said first magnetic roller and including a second magnetic roller parallel

to said first roller and located next to the same by magnetic attraction; band means passing about said second roller to prevent the latter from contacting said first roller; spool carrying means mounted on said carriage for carrying a weft thread spool; and a third roller parallel to said first and second rollers, turnably carried by said support means, and being located next to said second roller.
